CLAIM

The ornamental design for a handle for a shaving razor as shown and described.

DESCRIPTION

FIG. 1 is a front perspective view of a design of a handle for a shaving razor of the present invention;
FIG. 2 is a front view thereof;
FIG. 3 is a back view thereof;
FIG. 4 is a right side view thereof;
FIG. 5 is a left side view thereof;
FIG. 6 is a top view thereof;
FIG. 7 is a bottom view thereof;
FIG. 8 is a front perspective view of a second design of a handle for a shaving razor of the present invention;
FIG. 9 is a front view thereof;
FIG. 10 is a back view thereof;
FIG. 11 is a right side view thereof;
FIG. 12 is a left side view thereof;
FIG. 13 is a top view thereof;
FIG. 14 is a bottom view thereof;
FIG. 15 is a front perspective view of a third design of a handle for a shaving razor of the present invention;
FIG. 16 is a front view thereof;
FIG. 17 is a back view thereof;
FIG. 18 is a right side view thereof;
FIG. 19 is a left side view thereof;
FIG. 20 is a top view thereof; and
FIG. 21 is a bottom view thereof.
The broken lines disclosure of the shaver cartridge illustrates the environment of the handle for a shaving razor and forms no part of the claimed design. The remaining broken lines

illustrate portions of the handle for a shaving razor and form
no part of the claimed design.
